UNITED STATES PATENT OFFICE

111,775

DESIGN FOR A TRANSLUCENT CANDLE

William Seaver, Auburndale, Mass.

Application May 20, 1938, Serial No. 77,297

Term of patent 7 years

To all whom it may concern:

Be it known that I, William Seaver, a citizen of the United States, residing at Auburndale, in the county of Middlesex and State of Massachusetts, have invented a new, original, and ornamental Design for a Translucent Candle, of which the following is a specification, reference being had to the accompanying drawings, forming part thereof.

In the drawings:

Fig. 1 is a top plan view of a translucent candle showing my new design;

Fig. 2 is a side elevational view; and Fig. 3 is a vertical mid-sectional view thereof.

I claim:

The ornamental design for a translucent candle, substantially as shown.

WILLIAM SEAVER.
